UNITED STATES PATENT OFFICE

172,912

SAFETY RAZOR CASE

John D. Wark, Freeport, and Peter Schladermundt, Bronxville, N. Y., assignors to The Gillette Company, Boston, Mass., a corporation of Delaware

Application November 20, 1953, Serial No. 27,702

Term of patent 14 years

(Cl. D58—12.6)

To all whom it may concern:

Be it known that we, John D. Wark and Peter Schladermundt, citizens of the United States, residing respectively at 326 West Lena Ave., Freeport, Long Island, and 8 Park Avenue, Bronxville, New York, have invented a new, original, and ornamental Design for Safety Razor Case, of which the following is a specification, reference being had to the accompanying drawing, forming a part hereof.

Fig. 1 is a perspective view of a safety razor case, showing our new design.

Fig. 2 is a view in side elevation.

We claim:

The ornamental design for a safety razor case, as shown.
